UNITED STATES PATENT OFFICE

WADE MORTON, OF AUBURN, INDIANA, ASSIGNOR, BY MESNE ASSIGNMENTS, TO MANNING & CO., OF CHICAGO, ILLINOIS, A CORPORATION OF ILLINOIS

DESIGN FOR A COMBINATION AUTOMOBILE BODY, HOOD, AND RADIATOR

Application filed March 9, 1929. Serial No. 30,398. Term of patent 7 years.

To all whom it may concern:

Be it known that I, WADE MORTON, a citizen of the United States, and a resident of Auburn, county of De Kalb, and State of Indiana, have invented a new, original, and ornamental Design for a Combination Automobile Body, Hood, and Radiator, of which the following is a specification, reference being had to the accompanying drawing, forming a part thereof, and wherein—

Fig. 1 is a perspective view of an automo-

bile body showing my new design and Fig. 2 is a rear view of the same.

I claim:—

The ornamental design for a combination automobile body, hood and radiator substantially as shown.

WADE MORTON.
